DESIGN FOR A COAT

Charles Salerno, New York, N. Y.

Application October 25, 1941, Serial No. 103,899

Term of patent 3½ years

To all whom it may concern:

Be it known that I, Charles Salerno, a citizen of the United States of America, residing in New York city, county of New York, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

The characteristic feature of my design resides in the combination on the collared coat disclosed of the specific, contrasting yoke, in association with the princess seaming and slot pockets, all as shown.

I claim:

The ornamental design for a coat, substantially as shown and described.

CHARLES SALERNO.
